Application August 7, 1933, Serial No. 684,007
Renewed October 7, 1936

7 Claims. (Cl. 290—37)

This invention relates to automatic starting mechanism for internal combustion engines and more particularly to devices for controlling the operation of starting mechanism in accordance with the operating condition of the engine to be started.

It is an object of the present invention to provide a novel starter control which is simple and economical in construction and efficient and reliable in operation.

It is another object to provide such a device which insures accurate and dependable control of the starting operation.

It is a further object to provide such a device having a liberal range of adjustment for varying its controlling functions.

It is another object to provide such a device, the controlling characteristics of which are substantially unaffected by variations in external operating conditions and in the operating conditions of the associated components of the power plant.

Further objects and advantages will be apparent from the following description taken in connection with the accompanying drawings in which:—

Fig. 1 shows semi-diagrammatically a preferred embodiment of the invention in conjunction with a conventional type of internal combustion engine, the clutch pedal of which is used to control the initiation of the starting operation;

Fig. 2 is a similar view of a second embodiment of the invention in which the accelerator pedal of the engine is utilized as a control element;

Fig. 3 is a similar view of a third embodiment of the invention in which certain of the controlling functions are performed in response to the intake vacuum of the engine; and

Fig. 4 is a diagram showing graphically the results secured by separate field excitation as compared with the normal generator output.

Referring first to Fig. 1 of the drawings, there is illustrated an internal combustion engine indicated generally by numeral 1, and provided with a manually operable member 2 in the form of a clutch pedal of conventional type for controlling the transmission of power therefrom. A starting system for the engine is illustrated comprising a battery 3, grounded at 4, connected by a lead 5 to a magnetic starting switch 6 which in turn is connected by a lead 7 to a starting motor SM which is grounded at 8 to complete the starting circuit.

55 A control circuit for the magnetic starting

switch 6 is provided comprising the battery 3, lead 9, manual switch 11, which is preferably the ignition switch of the engine, lead 12, solenoid 13 of the magnetic starting switch, and lead 14 which is grounded through the armature of an engine-driven generator G to complete the control circuit. The generator G is employed to charge the battery 3 in the usual manner, the necessary connections being not illustrated since they form no part of the present invention. It will be understood that the connection of the control circuit to the generator G is in such a direction that the generator opposes the flow of battery current through the control circuit and thereby deenergizes the solenoid 13 when sufficient voltage has been built up in the generator.

According to the present invention, a field winding 15 of the generator G is connected by a lead 16 to the lead 12 adjacent the ignition switch 11. It will thus be seen that the field winding 15 is immediately energized by the full voltage of the battery 3 upon closure of the ignition switch 11.

A resistance element 17 is inserted in the lead 12 to the solenoid 13 and is designed to reduce the current flowing through the lead 12 to a mere holding value for said solenoid. In order to effect closure of the starting switch 6, a make and break device 18 of any suitable type is bridged around the resistance 17 and is operated by the clutch pedal 2 to close the bridging circuit when the clutch pedal is depressed. As here illustrated, the make and break device 18 comprises a rotary contact 19 connected by a lead 21 to one side of the resistance 17, and a fixed brush member 22 connected by a lead 23 to the other side of said resistance. The rotary contact 19 is normally out of engagement with the brush 22 but is moved into engagement therewith when the clutch pedal is depressed, by suitable means such as an arm 20 connected by a link 24 to the clutch pedal 2.

In the operation of this embodiment of the invention, and starting with the parts in the positions illustrated, closure of the ignition switch 11 causes battery current to flow through the control circuit and energizes the solenoid 13 to a holding value, but since this current traverses the resistance 17, the solenoid 13 is not sufficiently energized to close the starting switch. At the same time battery current flows through the lead 16 to the field winding 15 of the generator and energizes said field winding by virtue of the full battery voltage applied thereto. To effect the starting operation, the operator is then

called upon merely to depress the clutch pedal 2 in the usual manner prior to engaging the transmission gears. This moves the rotary contact 19 into engagement with the brush 22 whereby 5 the resistance 17 is bridged out and the solenoid 13 is fully energized, causing closure of the starting switch and initiation of the cranking operation. Release of the clutch pedal 2 does not 10 interrupt the cranking operation since, as above pointed out, sufficient current traverses the control circuit including the resistance 17 to hold the starting switch closed whereby cranking continues irrespective of the position of the clutch pedal. When the engine starts, the voltage developed by 15 the generator G rises sufficiently to cause deenergization of the solenoid 13 whereupon the starting switch opens, and is thereafter prevented from closing as long as the engine is self-operative.

20 The opening and closing voltages of the starting switch may be adjusted in any suitable way if desired. As here shown, the closing voltage is regulated by adjusting the compression of a spring 25 which holds the switch open; while 25 the opening voltage is similarly regulated by adjusting the compression of a loading spring 26 which is compressed by the final movement of the switch plunger after closure of the switch contacts.

30 It will be readily appreciated that one important advantage in the use of the resistance 17 to maintain the energization of the starting system irrespective of the position of the clutch pedal is that it permits the operator to move 35 the car by the starting mechanism when so desired. This is sometimes very important as, for instance, when an engine stalls while the car is in a position of danger, and is of course impossible with the conventional type of clutch 40 pedal controlled starting device.

It will be understood that when this embodiment of the invention is used in installations embodying an automatic clutch control, the make and break device 18 may be connected either 45 to the automatically operated clutch controlling element or to the clutch pedal only. The latter arrangement is shown in Fig. 1 in which the clutch operating lever 27 is arranged to be moved either by an automatic clutch control element 50 30 or by the pedal 2, and the link 24 is connected directly to said pedal. This arrangement has the advantage that in case of generator failure, the starter will not be actuated when the clutch is thrown out automatically, but only when 55 the operator depresses the clutch pedal 2.

The novel and improved results flowing from the excitation of the field winding 15 directly from the battery through the ignition switch 11 60 may best be appreciated by reference to Fig. 4 of the drawings which shows graphically the results secured by such separate field excitation as compared with the normal generator output. In this figure the curve 1a shows the terminal voltage of the generator with the field excited in the normal manner during the acceleration of the generator. Curve 1b shows the same during 65 the deceleration of the generator, the differences between curves 1a and 1b being due to the usual effect of hysteresis. Curve 2a shows the field current of the generator when the field is excited in the normal manner, during acceleration of the generator, and curve 2b for the corresponding 70 curve during deceleration of the generator. 75 Curve 3 shows the generated voltage when the

field is excited directly from the battery through the ignition switch, and curve 4 shows the corresponding field current.

It will be apparent from a study of these curves that the voltage available from the generator 5 at low speeds when separately excited is uniform and free from the effect of hysteresis, and much higher than with a conventional generator, and the variation in such voltage responsive to the changes in such low engine speeds is also much 10 greater. As a matter of fact, the voltage generated has been found to be substantially in direct proportion to the engine speed irrespective of whether the generator is being accelerated or decelerated, and irrespective of temperature 15 changes of the generator, etc. When it is considered that the controlling function of the generator preferably takes place on that portion of the curve below 300 R. P. M., it will be readily appreciated that the vastly increased range of 20 voltage made available by separate excitation of the generator field permits much superior regulation of the starting operation without necessitating critical adjustments of the controlling 25 elements.

Taking for instance a typical installation in which cranking speed is 200 R. P. M., the speed at which it is desired to interrupt cranking is 300 R. P. M., and the speed down to which re-cranking is to be prevented is 50 R. P. M. The voltages of a conventional generator corresponding thereto, taken from curve 1a, are 0.24 volt, 0.4 volt and 0.1 volt. The effective voltages impressed on the relay coil 13 by a 6-volt battery are then 5.76 volts, 5.6 volts, and 5.9 volts. It is necessary, therefore, to design a relay which will hold closed when the applied voltage is 5.76 35 volts, which will open when the applied voltage falls to 5.6 volts, and which will not reclose until the applied voltage rises to 5.9 volts. 40

In contrast to this, the corresponding generator voltages with a generator in which the field is excited from the battery according to the present invention are (curve 3) $2\frac{3}{4}$ volts, $3\frac{3}{4}$ volts and 1 volt, so that it is merely necessary to use a relay which will hold closed at $3\frac{1}{4}$ effective voltage, and open at $2\frac{1}{4}$ volts and will not reclose until the effective voltage rises to 5. This 45 obviously gives far greater latitude for variations in the characteristics of the component parts. 50

Referring now to the embodiment of the invention illustrated in Fig. 2, the starting circuit and the control circuit are similar to those shown in Fig. 1, the elements being similarly 55 numbered. In this embodiment of the invention, however, a make and break device 28 is arranged to be operated by a manual control member in the form of an accelerator pedal 29 for the engine as by means of a link 31 and an arm 32. The make and break device 28 is arranged preferably though not necessarily as shown to break the control circuit when the accelerator pedal 29 is completely released. For this purpose, the lead 12 is connected to a brush 33, and the make and break device is provided with a rotary electrode 34 normally out of engagement therewith, which electrode is connected by a lead 12a to the solenoid 13. The brush 33 65 is arranged to engage this electrode 34 upon initial depression of the accelerator pedal 29, and a second brush 35 is arranged to be engaged by said electrode upon further depression of the accelerator pedal, the brush 35 being adapted 70

to bridge the resistance 17 by virtue of a lead 36 connected thereto.

In the operation of this embodiment of the invention, starting with the parts in their idle positions as illustrated, closure of the ignition switch 11 energizes the field 15 of the generator. Initial depression of the accelerator pedal 29 closes the control circuit through the resistance 17, energizing the solenoid 13 to a holding value. Further depression of the accelerator pedal causes electrode 34 to engage the brush 35, thus shorting out the resistance 17 and causing full energization of solenoid 13 to close the starting switch 6. Cranking of the engine thereupon takes place and is continued irrespective of movement of the accelerator pedal 29 until the engine starts, unless the accelerator is completely released. In case of a false start of the engine of just sufficient force to demesh the starter pinion without accelerating the generator sufficiently to open the starting switch, it is merely necessary for the operator to release the accelerator pedal whereupon the starter is deenergized and the starting operation may then be repeated as above set forth.

It will be appreciated, however, that the greatly increased efficiency of the generator control according to the present invention reduces practically to the vanishing point the problem of preventing motor spin in case of false starts, since an engine explosion which is powerful enough to demesh the pinion is practically sure to energize the generator sufficiently to open the starting switch so that the cranking operation is automatically repeated.

The embodiment of the invention illustrated in Fig. 3 is similar to that shown in Fig. 1, except that the make and break device 38 is normally closed, and is automatically opened in response to intake vacuum whereby a fully automatic starter control is provided. As here shown, this make and break device comprises a fixed contact 39 and a movable contact 41 mounted on a flexible diaphragm 42 forming one wall of a chamber 43 suitably connected to the intake manifold 44 of the engine. Contact 39 is connected by a lead 45 to one side of the resistance 17, while contact 41 is connected by a lead 46 to the opposite side of said resistance. Contacts 39 and 41 are normally in engagement as shown but contact 41 is adapted to be withdrawn by intake vacuum of low value.

In the operation of this embodiment of the invention, closure of the ignition switch 11 causes energization of the generator field winding 15 from the battery, and also causes closure of the starting switch 6 since the resistance 17 is shorted out by contacts 39, 41. As soon as cranking starts, the vacuum in the intake manifold 44 causes contacts 39, 41 to open, but cranking continues by reason of the holding current for the starting switch which traverses the resistance 17. When the engine starts, the generator G causes deenergization of the solenoid 13 whereby the starting switch opens and remains open until contacts 39 and 41 close by failure of intake vacuum at the same time that the output of generator G falls below the predetermined minimum lock-out value. When these conditions are brought about by engine stall, the engine will be automatically restarted.

In order to prevent an immediate restart in case of engine stall, which might cause engagement of the starting pinion during a back-rock 75 of the engine, a time delay is preferably incor-

porated in the control. As here illustrated, this time delay is obtained by means of a disc 47 suitably fixed in the bottom of the chamber 43 and provided with a small aperture 48 communicating with the intake manifold connection. It will be readily appreciated that the reclosure of contacts 39, 41 will be delayed for the desired interval after an engine stall, by suitably proportioning the chamber 43 and selecting a disc 47 having the proper sized aperture for the particular class 10 of installation.

It has been found in certain installations made according to the present invention that when the lead 16 from the separately excited field 15 is directly connected to lead 12 of the control circuit as shown in Figs. 1 and 2, when the ignition switch 11 is opened to stop the engine, the breaking of the battery connection to said field may cause an inductive surge through the field in a reverse direction to the magnetizing current. This inductive surge may be of sufficient voltage to traverse the control circuit including the resistance 17 and actuate the solenoid 13 to close the starting switch. This causes a momentary actuation of the starting motor which is sometimes sufficient to cause the starter gear to attempt to engage the flywheel of the engine which causes an undesirable click as the starter pinion strikes the flywheel and might in time cause unnecessary wear of the parts.

In order to prevent this effect, the switch 11 may preferably be formed as shown in Fig. 3 as a two-pole switch, the field lead 16 being connected to one pole 51 and the control circuit lead 12 being connected to the other pole 52. The ignition circuit lead may obviously be connected to either of these poles. The switch 11 then constitutes means for separately simultaneously connecting the control circuit and the field winding to the battery and for disconnecting the field winding from the control circuit when the field winding is disconnected from the battery. Obviously this arrangement prevents the induced voltage of the field winding from affecting the control circuit.

Although certain embodiments of the invention have been shown and described in detail, it will be understood that other embodiments are possible and that changes may be made in the arrangement of the parts without departing from the spirit of the invention as defined in the claims appended hereto.

What is claimed is:

1. A power plant including an internal combustion engine, starting mechanism therefor including a magnetic starting switch, a control circuit for said starting switch including a battery, a manual switch and a make and break device; a manually operable power control member, means for operating said make and break device from said control member, a shunt resistor for maintaining the effective energization of the control circuit irrespective of opening of the make and break device, an engine-driven generator having a field winding connected in shunt with the portion of the control circuit including said make and break device, and means including said generator for maintaining said control circuit de-energized responsive to self-operation of the engine at or above a predetermined speed, said shunt resistor being of such value as to cooperate with the voltage of the generator in opposing flow of battery current through the magnetic starting switch to cause said switch to open at a predetermined engine speed.

2. A power plant including an internal combustion engine and a manually operable power control member, starting mechanism for said engine including a magnetic starting switch, a control circuit for said starting switch including a make and break device, connecting means whereby operation of the control member actuates said make and break device, a shunt resistor for maintaining the effective energization of the control circuit irrespective of the opening of the make and break device, an engine-driven generator having an armature and a field winding, connections whereby the armature voltage of the generator opposes energization of the starting switch, said shunt resistor being of such value as to cooperate with the voltage of the generator in opposing flow of battery current through the magnetic starting switch to cause said switch to open at a predetermined engine speed, and manually operable means for simultaneously controlling the energization of the control circuit and of said field winding.
3. A power plant including an internal combustion engine and a manually operable power control member, starting mechanism for said engine including a magnetic starting switch, a control circuit for said starting switch including a battery and a make and break device, connecting means whereby operation of the control member actuates said make and break device to cause closure of the starting switch, means for holding the starting switch closed, irrespective of opening said make and break device, an engine-driven generator having an armature and a field winding, connections whereby the generator opposes the flow of battery current through the control circuit, and manually operable means for simultaneously completing the control circuit and connecting said field winding directly to the battery.
4. A power plant including an internal combustion engine and a manually operable power control member, starting mechanism for said engine including a magnetic starting switch, a control circuit for said starting switch including a make and break device, connecting means whereby operation of the control member actuates said make and break device, a connection bridging said make and break device having such resistance as to reduce the flow of current in the control circuit to a holding value for the magnetic starting switch, an engine-driven generator having an armature and a field winding, means including said generator for opposing energization of the starting switch during self-operation of the engine, and a manually operable switch for simultaneously completing the control circuit and connecting said field winding directly to the battery.
5. A power plant including an internal combustion engine, starting mechanism therefor including a magnetic starting switch having an operating solenoid, a control circuit for said starting switch including a battery, a manual switch, a make and break device and said solenoid; means for operating said make and break device, a shunt resistor for maintaining the effective energization of the control circuit irrespective of opening of the make and break device, an engine-driven generator having a field winding so connected that when the control circuit is energized, said field winding is in shunt with the portion of the control circuit including said make and break device and said solenoid, and means including said generator for maintaining said control circuit deenergized responsive to self-operation of the engine at or above a predetermined speed, said shunt resistor being of such value as to cooperate with the voltage of the generator in opposing flow of battery current through the magnetic starting switch to cause said switch to open at a predetermined engine speed.
6. In combination with an internal combustion engine, starting mechanism therefor including a battery and a magnetic starting switch, a control circuit for said starting switch including said battery, a manual switch, and a make and break device, opening means for the make and break device responsive to self-operation of the engine, means in shunt with said opening means for holding the starting switch closed irrespective of opening of the make and break device, an engine-driven generator having a field winding, and means including said generator for deenergizing said control circuit and maintaining it inoperative during rotation of the engine above a predetermined speed, said field winding being connected directly to said battery through said manual switch.
7. In combination with an internal combustion engine, starting mechanism therefor including a magnetic starting switch, a control circuit for said starting switch including a battery, a manual switch and a normally closed make and break device, means responsive to intake vacuum for opening said make and break device, means for passing current of a holding value for said magnetic switch around said make and break device, and an engine-driven generator having an armature and a field winding, said armature being in circuit with the magnetic switch and make and break device, and said field winding being in shunt with the portion of the control circuit which includes the make and break device and the magnetic switch.

PAUL H. MAURER.
